UNITED STATES PATENT OFFICE

OLIVER C. DENNIS, OF WILMETTE, ILLINOIS

ELECTRIC VULCANIZER

Application filed February 4, 1927. Serial No. 165,872.

My invention relates to electric vulcanizers and has to do more particularly with the provision of a vulcanizing or heating unit adapted for application to articles to be vulcanized, and more particularly inner tubes, by the use of a **C** clamp. Such devices are carried as portable sets in the tool kit of the car and must be light, positive in operation, cheap to manufacture and preferably operative from the battery of the car.

An object of my invention is to provide a vulcanizer of this type which is simple in construction, compact in arrangement so as to provide the most effective heating, cheap to manufacture and portable or readily interchangeable with removable terminal clips readily applicable to the device although used in close quarters such as where applied by a **C** clamp. There are various other features and these will be more particularly pointed out in the ensuing part of the specification and appended claims.

For a better understanding of my invention reference is to be had to the accompanying drawing, in which—

Fig. 1 is a side elevation of the vulcanizer heat unit shown in full lines with the **C** clamp and tube shown in dotted lines;

Fig. 2 is a side elevation of the device with one-half thereof shown in section;

Fig. 3 is a side elevation of the spring terminal clip;

Fig. 4 is a right end elevation of Fig. 3; and

Fig. 5 is a sectional view along the line 5—5 of Fig. 4 showing more in detail the method of applying the conductor terminal to the clip.

Referring now more in detail to the preferred arrangement as illustrated, I provide a suitable metallically enclosed heat and electrically insulated heating element in the form of a casing including a front cupped portion A and rear cupped portion B adapted to fit into the front piece and be held therein by the turned in flange 6. The face portion 7 of the front cup A is concavo-convex, being formed of sheet metal, and I preferably use elements which when clamped between the front and rear cups are pressed to the contour of the vulcanizing face so that the heat ele-

ment is held in intimate relation therewith without intervening air spaces to prevent the full application of the heat. In the arrangement shown I use an insulating washer 8 next to the heating face of the device, this washer being preferably of mica. Next is a suitable electrical heating element 9 and placed against this is a heating insulating disk or plate 10 preferably of asbestos or similar material. I then place a suitable plate or disk 11 of a material which will protect the heat insulation plate 10, the element 11 being of suitable heat resistant material. In the preferred device I use a disk 11 of sheet steel. The rear portion B of the casing has a central indented portion 12 adapted to receive the clamping screw 13 of the **C** clamp 14 for clamping the device against the tube 15 or other element which is to be vulcanized. For instance, in patching an inner tube as 15 the patch is placed between the tube and vulcanizing face of the device, which is concave so as to fit over the patch. Now as to the rear portion B, this is preferably cupped so as to provide a terminal space 16 through which the conductor terminals of the heat element pass to the terminal post.

There are a number of advantages in the terminal and construction arrangement of my device, in that by placing the terminal posts upon the rear cup the terminal conductors of the heating element are connected to the posts and this permits bending or forming the heating element and its protective disks so as to conform to the rounded face of the device and be pressed into intimate relation therewith.

As to the terminal post used this is in the form of a tubular post 17 insulatingly secured to the rear cup preferably by insulating washers 18 with the end 19 of the post turned over to bind the parts together. Thus the terminal posts are secured to the rear cup before the casing is assembled. By using a tubular post with a passage therethrough the terminal conductors 20 of the heating element are slipped up into the passage through the terminal post and the rear cup B then placed into the front cup A over the heat element and protective disks. The conductors 20 ex-

tend up through the hollow of the post and then are drawn taut and the end 21 of the post pressed together to clamp the conductor in the post and hold it in intimate electrical contact with the posts. The projecting end of the conductor 20 is then clipped off.

It will thus be seen that I have provided a very compact and effective heating unit.

Now as to the connection of the electrical conductors with the device, I have provided a simple and effective spring terminal clip adapted for use with the simple terminal posts 17. Thus the heating element may be readily connected to and disconnected from the power wires which may be conductors used for other purposes on the car or be permanently connected with a battery source and coiled up in the car at some accessible place but with the heating element permanently attached thereto. This spring clip is in the form of a polygonal sheet metal member, preferably a triangular portion 22 having overlapping ends 23-24 with openings 25-26 respectively therein. With the clip disconnected from the terminal these openings 24-25 are normally non-registering, but by pressing the clip together until these openings register, the device may be slipped over the end of the terminal post until the overlapping ends snap into the annular recess 27 by which the clip is retained on the post. To release the clip it is only necessary to press it together until the openings register sufficiently to permit withdrawal of the clip over the post. To fasten the electrical conductor to the clip I provide an extension 28 adapted to be wrapped around and clipped onto the conductor as 29 and one wall of the clip is sheared so as to provide an offset portion 30 under which the end 31 of the conductor is inserted. Thereafter the portion 30 is pressed downwardly toward the wall of the clip, thereby holding this end 31 in the clip and also in intimate electrical contact with the device.

What I claim as new and desire to secure by United States Letters Patent is:—

1. In an electric vulcanizer, a sheet metal heat element enclosing casing having a cupped back wall shaped to provide a terminal conductor space therein, a heating element in the casing, and tubular terminal members insulatingly secured in the back wall where it is shaped to receive them and having a passage extending therein to receive terminal conductors from the heating element.

2. In an electric vulcanizer, a sheet metal heat element enclosing casing having a cupped back wall shaped to provide a terminal conductor space therein, a heating element in the casing, and tubular terminal members insulatingly secured to the back wall and having a passage extending therein to receive terminal conductors from the heating element, said terminal members being compressed by force

to clamp the received conductors therein and hold them in intimate electrical contact with the terminals.

3. In an electric vulcanizer, a sheet metal casing comprising front and rear cupped portions, one of said members being shaped to be placed into the cup of the other to be clamped therein, an electrical heating element positioned between the front and rear casing members to be clamped therebetween, and a pair of tubular terminals insulatingly secured in the rear casing portion each with a passage extending therethrough to receive a terminal conductor of the heating element to permit drawing such conductor out through the passage until taut when the cup portions and heating element terminal conductor are clamped together.

4. In an electric vulcanizer, a sheet metal cupped front member having a concavo-convex face plate with a concave patch receiving face, a heating element, heat and electrical insulating plates placed adjacent the heating element, and a cup-shaped rear cap set into the side wall of the front member and said plates being pressed into intimate relation with each other, with the heating element and the inner convexo face of the front member held together by a turned in flange of the side wall of said front member.

5. In an electric vulcanizer, a sheet metal casing having front and rear cupped portions, the front cupped portion having a concavo-convex face, a mica sheet in contact with the full inside portion of said face and having the same curvature, a heating element contoured to lie against the mica disk throughout, a heat insulating disk having the same contour as the mica disc and engaging the opposite side of the heating element, with apertures therein through which terminals of the heating element extend, a metal washer in back of the heat insulating disk, the rear cupped casing having a flange-like edge lying on top of the metal washer, and the front casing being turned over to clamp the two casings together, and maintain the front casing face, mica disk, heating element, and heat insulating washer in intimate contact, and terminal posts on the rear casing for receiving the heating element terminals in clamping relation.

6. In an electric vulcanizer, a sheet metal casing having front and rear cupped portions, the front cupped portion having a concavo-convex face, a mica sheet in contact with the full inside portion of said face and having the same curvature, a heating element contoured to lie against the mica disk throughout, a heat insulating disk having the same contour as the mica disc and engaging the opposite side of the heating element, with apertures therein through which terminals of the heating element extend, a metal washer in back of the heat insulating disk, the rear

cupped casing having a flange-like edge lying on top of the metal washer, and the front casing being turned over to clamp the two casings together, and maintain the front casing face, mica disk, heating element, and heat insulating washer in intimate contact, terminal posts on the rear casing for receiving the heating element terminals in clamping relation, said terminal posts comprising tube like members clamped into position on the casing in apertures thereon with insulating washers between the post and the casing, the wire being clamped by the collapsed side wall of the tube and extending taut between the tube and the heating element.

7. In an electrical vulcanizer a two part casing, one part with a concavo-convex surface for engaging a patch and the other part cup shaped to extend above the first part, a heating element held adjacent said concavo-convex surface, and tubular terminal elements insulatingly secured in holes in the cup shaped portion of the casing with a continuing passageway from the inside to the outside of the casing thru each tubular terminal, the leads from the heating element being extended into said passageways and held therein in contact with the terminal by the partial collapsing of the portion of the tube on the outside of the casing.

8. In an electrical vulcanizer a two part casing, one part with a concavo-convex surface for engaging a patch and the other part cup shaped to extend above the first part, a heating element held adjacent said concavo-convex surface, and tubular terminal elements insulatingly secured in holes in the cup shaped portion of the casing with a continuing passageway from the inside to the outside of the casing thru each tubular terminal, the leads from the heating element being extended into said passageways and held therein in contact with the terminal by the partial collapsing of the portion of the tube on the outside of the casing, electrical connection with the vulcanizer being formed by engaging the exposed portion of said terminals, the projecting tubular portion being shaped to facilitate connection thereto.

50 In witness whereof, I hereunto subscribe my name this 27th day of January, 1927.

OLIVER C. DENNIS.
